TELEPHONE-EXCHANGE SYSTEM.

1,046,634.

Specification of Letters Patent.

Patented Oct. 8, 1912.

Application filed March 17, 1909. Serial No. 483,927.

To all whom it may concern:

Be it known that I, ELMER R. CORWIN, citizen of the United States, residing at Chicago, in the county of Cook and State of Illinois, have invented a certain new and useful Improvement in Telephone-Exchange Systems, of which the following is a full, clear, concise, and exact description, reference being had to the accompanying drawings, forming a part of this specification.

My invention relates to telephone exchange systems, and relates more particularly to trunk line equipment employed for uniting sub-stations whose lines extend to different exchanges.

Among the objects of my invention are, first, the provision of a trunk circuit extending between exchanges, which serves metallically to separate the batteries at the two exchanges; second, the provision of means whereby proper control is had over supervisory apparatus where a trunk circuit fulfilling the first object of my invention is employed.

I will explain my invention more fully by reference to the accompanying drawing, showing the preferred embodiment thereof, in which I have suggested, at A, one exchange, at B, another exchange, and at C, a trunk line equipment, all but the portion thereof having the jack and the signaling mechanism associated with the jack being understood to be at the exchange B, the said trunk line jack and the signaling apparatus associated with said jack being understood to be at the exchange A. At the exchange A, I have shown jack switches belonging to the lines of two subscribers M, N, one of many cord circuits *a*, and a group of multiplied trunk line jacks *b* having sleeve and tip contacts which are connected or adapted for connection respectively with the tip contact of the trunk plug *c* and the sleeve contact of such trunk plug, the conductor *d* extending between the tip spring of the jack *b* and the tip of the plug *c*, while the conductor *e* extends between the sleeve contact of the jack *b* and the sleeve of the plug *c*.

Before describing the mechanism and circuits of the trunk circuit intervening between the terminals *b* and *c* of the trunk circuit (the terminal *b* being at exchange A and the terminal *c* at exchange B), I will describe the equipment of one of the two telephone lines, O P which extend to the ex-

change B. Each of the telephone sub-stations shown in association with the exchange B has a telephone switch-hook 1 adapted, when holding the receiver 2, to include a call bell 3 in bridge of the limbs 4, 5 of each line, in which bridge is included a condenser 6. Other sub-station outfits may be used. When the switch-hook at each station is relieved of the telephone receiver thereat, the receiver, in rising, opens the bell bridge and includes the telephone transmitter 7 in series with the limbs 4, 5 of the associate telephone line and in series with the receiver 2, an impedance coil 8 being then included in shunt of the telephone receiver. The limb 4 of each telephone line includes an electro-magnet or relay winding 9 and the limb 5 of each telephone line includes an electro-magnet or relay winding 10, the windings 9 and 10 being upon a common magnetic core. The limbs of the telephone lines are united by a common battery 11, whereby when a receiver is removed from its switch-hook at a calling sub-station, the windings 9 and 10 are energized, and inasmuch as these windings are cumulatively wound, the core of said windings is caused to operate an armature 12, which serves to include a signal device, preferably a lamp 13, in a circuit which may be traced from the upper terminal of the battery 11 to the alternate contact of the armature 12 (by way of mechanism which will be mentioned later, the signal lamp 13 corresponding to the station from which the telephone receiver has been removed, assuming such station to be a calling station, a jack spring 14, a thimble 15 with which the jack switch 14 is separably engaged, to the lower terminal of the battery 11. The lamp 13, when thus included in circuit, conveys a steady signal to the operator, who is thereby informed that the subscriber whose line corresponds to the lamp 13 desires to initiate a call.

When two of the subscribers whose lines terminate at the exchange B desire connection with each other, they may be united by suitable cord connecting apparatus, such as indicated at 18. If a subscriber whose line is associated with the exchange A desires connection with a subscriber whose line is associated with the exchange B, the trunk circuit having the terminals *b* *c* is brought into service, the terminals of a cord connecting circuit *a* being engaged with the trunk

line jack *b* and a jack of a calling subscriber whose line extends to the exchange A, while the terminal plug *c* of the trunk circuit is engaged with the jack of a called subscriber whose line extends to the exchange B, and in order more clearly to understand the description which is to follow, I will at present omit a description of the operations through the means of which the trunk circuit is thus brought into service and will assume that the trunk line will thus connect a subscriber of exchange B with a subscriber of exchange A through the agency of the instrumentalities *a b c*, as has been described.

15 By inserting the plug *c* within the jack of a called subscriber, the tip of the plug *c* is caused to engage the line spring 19 of such jack, the sleeve of such plug engaging the spring 20 of said jack (the springs 19 and 20 constituting talking contact terminals of the called line) while the heel or body of the plug *c* engages the thimble 15. The spring contacts 14 and 19 are mechanically connected, so that when the tip of the plug *c* engages and holds up the tip line spring 19, the contact spring 14 is elevated and maintained elevated during the presence of the plug *c* in the engaging jack, to disconnect the contact 14 from the thimble 15 and bring 25 and maintain said contact 14 in engagement with an alternate contact, so that the signal device 13 is not then capable of conveying a line signal as it otherwise would were the parts 14 and 15 in connection.

30 35 When a connecting plug is inserted in the jack of a called line (the line P), the condition is such that the circuit for the signaling current is established, which circuit may be traced from the upper terminal of the calling generator 24, to the switch arm 25, the normal contact of the lower armature switch of relay 26, the sleeve of the plug *c*, the line spring 20 of the engaged jack, to the limb 5 of the called line, where the calling 40 current divides, a sufficient portion passing through the called subscriber's bell 3 by way of the limb 5, the switch-hook 1, the condenser 6, the limb 4, the coil 9 of the called subscriber's line relay, to the lower terminal 45 of the calling generator 24, to operate the bell 3. When the called subscriber responds, he causes an energization of the relay 26, thereby to disconnect the calling generator 24 from the called subscriber's line, said relay 26 having an armature switch 26¹ provided with a normal contact that follows the armature switch 26¹ in its movement until said armature switch engages its alternate contact, whereupon another circuit is closed 50 through the relay 26 that is maintained closed until broken, upon the withdrawal of the plug *c* from its engaging jack. Claims 60 upon the novel signaling and ringing features herein illustrated are included in a 65 copending application.

Having thus described in a general way the equipment at the exchanges A and B, and generally the behavior thereof when a call is initiated at the exchange A for a line terminating at exchange B, I will now describe the features of the system herein shown which form the subject matter of my present invention, it being understood that any suitable equipment may be employed at the exchanges A and B with which the novel features of my invention are adapted for coöperation. When the operator at exchange A inserts the plug of a cord circuit *a* in the jack *b* of a trunk line *d e*, for the purpose of connecting a calling line terminating at exchange A with a called line terminating at exchange B, said operator at exchange A, by the manipulation of a suitable ringing key, includes the ringing generator *F* in bridge of the sides *d e* of the trunk line circuit, thereby occasioning the operation of the drop signal device *f¹* located in front of the operator having charge of the plug *c*, the signal device *f¹* preferably including a shutter which is allowed to fall when said signal device receives current from the generator *f*. The signal device *f¹* constitutes a clearing-out signal device or supervisory signal device. The energizing circuit for the signal device *f¹* may be traced from the sleeve side of the inserted plug belonging to the set *a*, to the strand *e* of the trunk circuit which is conductively connected with the sleeve *b* of the trunk line jack to the signal device *f¹*, through the condenser *f²*, to the normal contact of the armature switch *g*, to the tip contact of the trunk line jack at exchange A, to the tip of the plug received by said jack, thence to the generator of alternating current *f*. The operator, in response to the signal conveyed at *f¹*, throws her manually operated listening key to the answering position, in which position the contact springs *h h* are spread apart, thereby to connect said contact springs with their alternate contacts, each spring having an alternate contact which constitutes the terminal of the operator's telephone receiver *h¹*. Having ascertained the connection desired, the operator inserts the plug *c* within the jack of the called subscriber (for example, the line P), with results that have hitherto been described and which are set forth in my said co-pending application.

One of the objects of my present invention is to provide means for preventing the operation of the clearing-out or supervisory signaling apparatus present in the cord connecting outfit *a* that forms a part of the connection between the calling subscriber whose line terminates at exchange A and the called subscriber whose line terminates at exchange B, whenever the trunk operator deems it desirable to do so, whereby the operation of such supervisory apparatus as-

sociated with such cord a may be prevented, even though the called subscriber has restored his receiver upon its switch-hook, or the operator has withdrawn the plug c from connection with the called subscriber's line. This feature of my present invention becomes of advantage when either the called subscriber P or the trunk operator, realizing that it is desirable to have the calling subscriber connected with another line instead of the line P , may bring about such a new connection without thereby apprising the operator at exchange A of the fact that the subscriber P has restored his telephone receiver upon its switch-hook or that the trunk line operator had withdrawn the plug c . The supervisory or clearing-out apparatus associated with the cord circuit a at the exchange A is so well known as hardly to require description, the supervisory apparatus illustrated being one of several types that may be employed in practising my invention. The form of signaling apparatus indicated includes two supervisory relays a^1 and a^2 , the relay a^1 being associated with the answering end of the link circuit a and the relay a^2 being shown in association with the connecting end of the link circuit a . The armatures of these relays, when inert, connect the supervisory lamps a^3 a^4 in circuit with the grounded common battery at the exchange A , whereby circuits are closed through these lamps a^3 a^4 when the relays a^1 a^2 are deenergized when the associate plugs are in engagement with jacks.

Inasmuch as the operation of the clearing-out or supervisory signaling apparatus associated with the cord a and governed by the called subscriber, is prevented by a metallic connection between the sides of the telephone circuit established at the called station when the telephone receiver is removed from its switch-hook (this metallic connection, in the embodiment of the invention illustrated, including the transmitter 7, receiver 2, the impedance coil 8, and the switch-hook 1), I provide a substitute metallic connection which is bridged across the trunk strands d and e when the trunk operator knows that the called subscriber is liable to restore his telephone upon its switch-hook or when the trunk operator is about to withdraw the plug c (and only in case the trunk operator does not desire to have a disconnect signal sent in to the exchange A), to which end I employ a switching device including a spring i permanently connected with a section of the side d of the trunk line, said contact spring i having a contact normally separated therefrom and which constitutes a terminal of the bridge conductor which I import into the system for the purpose above stated, which bridge conductor includes an impedance device i^1 , and has its other terminal connected with the

side e of the trunk circuit, whereby when the switch spring i is actuated, a bridge is connected across the sides of the trunk circuit, in which bridge the impedance device i^1 is included for the purpose of preventing voice currents from being shunted across the sides of the trunk circuit. For sake of convenience, the switching device i is mechanically mounted upon a spring lever of the operator's listening key k , the lever selected being one of the two levers shown upon the left of the listening key k , which, when operated, serve to include the operator's telephone set in circuit, so that she may converse with the called subscriber to the exclusion of the calling subscriber and the calling subscriber's operator, the operator allowing her listening key to remain in its holding position, in which the retarding device i^2 is included in bridge in case she is advised by the called party to connect the calling subscriber with another line or if for any reason the operator desires to remove the plug c from the jack of the called line and to engage said plug with the jack of another line, the operator still allowing the listening key to remain in this holding position until the operator has inserted a plug in the jack of the newly called party, whereupon the operator may restore her telephone key to its normal position, for reasons which will hereinafter be set forth. The operator may also, if she desires, perform other pressing duties during the time that her listening key is in the holding position and while the plug c is out of jack engagement. The operator's listening key thus has three positions, one, the answering position, in which the operator is adapted to listen to the wants of the calling subscriber conveyed either by the calling subscriber or the calling subscriber's operator, in which answering position the switch springs h are spread apart to bridge the operator's telephone set h^1 across the sides of the telephone circuit; two, the normal or central position, in which the operator's telephone is cut out of circuit; and, three, the holding position, in which the switch parts at the left of the key k are operated to include the impedance device i^1 in bridge of the trunk sides, thereby to hold or prevent the operation of the clearing-out or supervisory apparatus associated with the connecting end of the cord circuit a that would otherwise be operated, when the plug c is withdrawn from its jack or the called subscriber has restored his receiver upon its switch-hook.

When the telephone key k is in the holding position, the operator is adapted to talk with the called subscriber without permitting the voice currents to pass to the exchange A , as has been stated, and when the telephone key k is in the answering position (the right-hand position), I desirably con-

fine the operator's telephone to association with the portion of the trunk line extending to the exchange A, so that the trunk operator is not able to bridge her telephone in the combined circuit extending between two connected subscribers. To this end, I include the armature switches l and their normal contacts in serial relation with the listening key springs h , so that when the armature switches are unattracted, the operator's telephone may be included in circuit when the listening key is thrown to its answering position, there being provided an electro-magnet m for operating the switches l when the plug c is inserted within the jack of a called subscriber, to prevent the operator's telephone from being included in circuit when the listening key h is in the answering position, so that the operator may only listen to the called subscriber after a trunk line connection has been put up, for the purpose of securing secrecy of service. The circuit for the magnet m which is closed by the plug c when connected with a called line, may be traced from the upper terminal of the battery 11, through the winding of the magnet m , the body portion of the plug c , the thimble 15, to the lower terminal of said battery. When the magnet m is energized and the switches are thereby attracted, the trunk operator's circuit is opened at l , securing the results specified, the normally engaged contacts of the switches l being in serial relation with the contacts of the key h and furnishing the means whereby these latter contacts are connected with the talking sides of the trunk circuit. A relay n is included in circuit when the called subscriber responds, so that the armature switch g is attracted to place the indicator f^1 in open circuit, to prevent said indicator from being again operated until the relay n is deenergized. The circuit for relay or magnet n may be traced from the upper terminal of the battery 11, through the winding of the magnet n , to the sleeve of the plug c by way of the now attracted lower armature switch of the relay 26, the sleeve spring 20 of the called subscriber's jack, over the line of the called subscriber, through the winding 9, to the lower terminal of the battery 11. The relay 26 is included in a local circuit after the plug c has been inserted, which plug c governs said local circuit, the relay 26 bringing the relay n into the control of the subscriber P and permitting the subscriber P to retain such control until the plug c is withdrawn. When the electro-magnet n is thus energized, its topmost and lowermost armature switches are actuated to complete the sides of the trunk circuit. The armature switch g governed by the electro-magnet n when actuated, engages an alternate contact provided therefor, to establish a bridge across

the sides of the trunk circuit to hold or prevent the operation of the clearing-out or supervisory signal associated with the connecting end of the cord circuit a (said supervisory or clearing cut signal also being similarly held in case the subscriber P were a calling subscriber), and in order to avoid the necessity of employing an additional bridge conductor, I connect the alternate contact of the armature switch g with the contact opposed to the spring i , and inasmuch as said armature switch g is connected with the switch spring i , the impedance device i^1 is included in bridge between the sides of the trunk circuit when the armature switch g engages its alternate contact. In case the trunk operator is to receive the knowledge of the wants of the calling subscriber from the calling subscriber, instead of the calling subscriber's operator, I provide the impedance device i^1 with another terminal i^2 which is opposed to the upper spring h , so that when the trunk operator has her listening key in its answering position, the bridge conductor containing the impedance device i^1 is again included in bridge of the sides of the trunk circuit to prevent the operation of the supervisory or disconnect signal apparatus associated with that end of the cord circuit a which engages the trunk line jack and at the exchange A.

After the trunk operator inserts the plug c in the jack of a called line, the operator restores her listening key to its central or side position, in which the terminals of the impedance device i^1 associated with the listening key are disconnected from the springs of the listening key, and in order to prevent the operation of the clearing-out or supervisory signal device at the ringing end of the cord circuit a , still another terminal for the impedance device i^1 is brought into connection with the side d of the trunk circuit, this last terminal of the impedance device i^1 being the alternate contact of the armature switch l . The alternate contact of the armature switch l is connected with the impedance device i^1 by way of the uppermost armature switch of the relay 26 and the contact engaging said armature switch when said armature switch is in its unattracted position. The magnet 26 is energized when the called subscriber responds, as has been set forth, so that the bridge containing the impedance device i^1 is again broken so far as the alternate contact of the switch l is concerned, but inasmuch as the magnet n is energized when the called subscriber responds, the bridge for the impedance device i^1 is established at the alternate contact of the armature g , as has been described.

I speak of preventing the operation of the clearing-out or supervisory signal device at the right-hand end of the cord circuit a ,

meaning thereby that such signal device is prevented from presenting a clearing-out or supervisory signal.

It will be observed in the system I have described, that the clearing-out or disconnect device at the right-hand end of the cord circuit a is governed by the metallic connection effected at the station P or other called station when the receiver thereat is removed, 10 this metallic connection being in continuous circuit relation with the magnet n when the called subscriber's receiver is removed from its switch-hook, the magnet n governing the bridge which is adapted to prevent 15 or permit of the operation of said clearing-out or supervisory signal.

In the preferred embodiment of my invention, I divide the trunk circuit into two telephonically united sections that are not 20 metallically continuous, there being employed condensers $o \cdot p$ in the sides of the trunk circuit for separating each side into two parts so far as direct currents are concerned, but preserving the continuity of 25 each side of the cord circuit so far as telephonic currents are concerned.

The bridge conductor including the impedance device i^1 is adapted for connection with the trunk conductors $d \cdot e$ on those sides 30 of the condensers $o \cdot p$ that are connected or adapted for connection metallically with the trunk line jack at the exchange A. By this arrangement I am enabled to employ batteries of suitable voltages for the trunk line 35 circuits and the exchange equipment at A, whether such voltages are similar or wide apart in value. I, furthermore, am enabled to eliminate all grounds from the battery terminals. The impedance i^1 is normally 40 grounded through the signal lamp q by way of the normal contact of an armature switch q^1 belonging to a relay q^2 . When the trunk line operator at C desires to signal the switch-board operator at A, the trunk line 45 operator, as a consequence of the operation of her listening-key, completes a circuit through the lamp q , which may be traced from the grounded battery at exchange A through the lamp q , the armature switch q^1 50 of the relay q^2 , the impedance i^1 , switch part i , to the grounded armature switch q^4 . By means of the system illustrated, the trunk line operator may signal the exchange operator and the exchange operator may signal 55 the trunk line operator without the use of special order wires. The trunk line equipment enters into the apparatus employed for effecting transmission of signaling current from the trunk line operator to the exchange 60 operator, and vice versa, whereby special order wire equipment intervening between these operators, is not required. The trunk circuit employed thus constitutes a two-way 65 trunk circuit, by which is meant a trunk circuit employed for the purposes of establish-

ing telephonic connection between telephone lines terminating at different exchanges, to enable conversation between the trunk line operator and exchange operator and to enable each of these operators to signal the 70 other.

In some of the claims the expression "two-way" has been used in connection with the expression "trunk circuit," such expression having the meaning here set forth.

It will be seen that there is another object accomplished by the provision of the bridge conductor that includes the impedance device i^1 , for it will be apparent that as soon as a subscriber indicated at the right-hand, 75 has restored his telephone receiver upon its switch-hook, the bridge containing the impedance i^1 will be opened, thereby clearing the jack ends of the trunk lines, so that the trunk lines will test free when an operator 80 at station A applies a testing plug thereto. I have not illustrated any particular testing means for the trunk line jacks, as any well known means may be employed for the purpose.

The magnet 26, when included in local circuit, prevents the re-inclusion of the generator 24 in circuit with the trunk until the plug c has been withdrawn. If the operator at exchange A should happen to select a 90 trunk circuit which tests free and which still has its plug c in a jack, such operator at exchange A may operate the signal device f^1 by means of her calling key a^5 , but will not operate the signal receiver of the line still 95 connected with the selected trunk by the trunk plug c . Thus the generator f at the exchange A is prevented from being included in circuit with the signal receiver 3 at station P by the magnet 26, although current from this generator F is permitted to 100 traverse a part of the trunk when the key a^5 is operated, in order to work the signal device f^1 .

I am aware that two-way trunk circuits 110 have been hitherto proposed, but they have not been used in number, because in their use, objections have been encountered which are cured by the system of my invention.

While I have herein shown and particularly described the preferred embodiment of my invention, I do not wish to be limited to the precise construction and arrangement set forth, as changes may readily be made without departing from the spirit of the invention.

Having thus described my invention, I claim as new and desire to secure by Letters Patent the following—

1. A telephone exchange system including 125 telephone lines extending from sub-stations to different exchanges, a voice-current-conveying two-way trunk circuit for uniting said lines in conversation, said trunk circuit being formed in sections that are un-united 130

metallically but are united telephonically, clearing-out or supervisory signaling apparatus at one exchange adapted for association with one of said sections of the trunk 5 circuit in the process of establishing a connection through said latter exchange, means associated with the other section of said trunk circuit for governing the aforesaid supervisory or clearing-out signaling apparatus, and operator-controlled switching mechanism associated with the section of the trunk circuit that is not metallically connected with the supervisory or disconnect signaling apparatus, for preventing false 10 operation of said clearing-out or supervisory signaling apparatus.

2. A telephone exchange system including telephone lines extending from sub-stations to different exchanges, a voice-current-conveying trunk circuit for uniting said lines in conversation, said trunk circuit being formed in sections that are un-united metallically but are united telephonically, clearing-out or supervisory signaling apparatus at one 20 exchange adapted for association with one of said sections of the trunk circuit in the process of establishing a connection through said latter exchange, means associated with the other section of said trunk circuit for 25 governing the aforesaid supervisory or clearing-out signaling apparatus, operator-controlled switching mechanism jointly controlled by the terminal-connecting element of the link circuit, which connecting element 30 is not metallically connected with the supervisory or clearing-out signaling apparatus and is associated with the aforesaid means, and a switching device adapted to co-act with 35 said terminal element, said switching mechanism serving, when operated, to prevent false operation of said clearing-out or supervisory signaling apparatus.

3. A telephone exchange system including telephone lines extending from sub-stations 45 to different exchanges, a voice-current-conveying trunk circuit for uniting said lines in conversation, said trunk circuit being formed in sections that are un-united metallically but are united telephonically, clearing-out or supervisory signaling apparatus at one exchange adapted for association with one of said sections of the trunk circuit in the process of establishing a connection through said latter exchange, means associated with the other section of said trunk 50 circuit for governing the aforesaid supervisory or clearing-out signaling apparatus, a source of ringing current, subscriber controlled switching mechanism for including 55 the same in circuit relation with the called station that is connected with the section of the link circuit in association with the aforesaid means, and which said section of the link circuit is not metallically connected 60 with the supervisory or disconnect signaling 65

apparatus, said switching mechanism, when including the source of ringing current in circuit, serving to prevent the operation of the aforesaid means, to prevent false operation of said clearing-out or supervisory signaling apparatus. 70

4. A telephone exchange system including telephone lines extending from sub-stations to different exchanges, a voice-current-conveying trunk circuit for uniting said lines in conversation, said trunk circuit being formed in sections that are un-united metallically but are united telephonically, clearing-out or supervisory signaling apparatus at one exchange adapted for association with one of said sections of the trunk circuit in the process of establishing a connection through said latter exchange, means associated with the other section of said trunk circuit for governing the aforesaid supervisory or clearing-out signaling apparatus, a signal device associated with the trunk circuit and operable from the exchange to which the trunk circuit extends, and relay mechanism at the trunk circuit station for dissociating said signal device, said relay mechanism including a switching device that serves to permit the operation of the aforesaid means to avoid false operation of said clearing-out or disconnect signaling apparatus. 75 80 85 90 95

5. A telephone exchange system including telephone lines extending from sub-stations to different exchanges, a voice-current-conveying trunk circuit for uniting said lines in conversation, said trunk circuit being formed in sections that are un-united metallically but are united telephonically, clearing-out or supervisory signaling apparatus at one exchange adapted for association with one of said sections of the trunk circuit in the process of establishing a connection through said latter exchange, means associated with the other section of said trunk circuit for governing the aforesaid supervisory or clearing-out signaling apparatus, an operator's telephone equipment adapted for connection with the section of the trunk circuit which is metallically connected with said supervisory or disconnect signaling apparatus, and electro-magnetic mechanism governed by a trunk circuit apparatus, for dissociating said operator's telephone from the trunk circuit, said electro-magnetic mechanism including a switching device that serves to prevent the operation of the aforesaid means, to prevent false operation of said clearing-out or supervisory signaling apparatus. 100 105 110 115 120

6. A telephone exchange system including telephone lines extending from sub-stations to different exchanges, a voice-current-conveying trunk circuit for uniting said lines in conversation, said trunk circuit being formed in sections that are un-united metal- 125 130

5 lically but are united telephonically, clearing-out or supervisory signaling apparatus at one exchange adapted for association with one of said sections of the trunk circuit in the process of establishing a connection through said latter exchange, means associated with the other section of said trunk circuit for governing the aforesaid supervisory or clearing-out signaling apparatus, an operator's telephone equipment adapted for connection with the section of the trunk circuit which is metallically connected with said supervisory or disconnect signaling apparatus, and switching mechanism for including the operator's telephone equipment in circuit with the trunk circuit and serving to prevent effective operation of the aforesaid means to prevent false operation of said clearing-out or supervisory signaling apparatus.

10 15 20

paratus, and switching mechanism for including the operator's telephone equipment in circuit relation with the connecting end of the trunk circuit and serving to prevent effective operation of the aforesaid means, to prevent false operation of said clearing-out or supervisory signaling apparatus.

9. A telephone exchange system including telephone lines extending from sub-stations to different exchanges, a voice-current-conveying trunk circuit for uniting said lines in conversation, said trunk circuit being formed in sections that are un-united metallically but are united telephonically, clearing-out or supervisory signaling apparatus at one exchange adapted for association with one of said sections of the trunk circuit in the process of establishing a connection through said latter exchange, means associated with the other section of said trunk circuit for

75 80 85

7. A telephone exchange system including telephone lines extending from sub-stations to different exchanges, a voice-current-conveying trunk circuit for uniting said lines in conversation, said trunk circuit being formed in sections that are un-united metallically but are united telephonically, clearing out or supervisory signaling apparatus at one exchange adapted for association with 25 one of said sections of the trunk circuit in the process of establishing a connection through said latter exchange, means associated with the other section of said trunk circuit for governing the aforesaid supervisory or clearing-out signaling apparatus, an operator's telephone equipment adapted for connection with the section of the trunk circuit which is metallically connected with said supervisory or disconnect signaling apparatus, and switching mechanism for including the operator's telephone equipment in circuit relation with the answering end of the trunk circuit, and serving to prevent effective operation of the aforesaid means 30 to prevent false operation of said clearing-out or supervisory signaling apparatus.

governing the aforesaid supervisory or clearing-out signaling apparatus, an operator's telephone equipment adapted for connection with the section of the trunk circuit which is metallically connected with said supervisory or disconnect signaling apparatus, and switching mechanism for limiting the operator's telephone equipment to association with the answering end of the trunk circuit and serving to prevent operation of the aforesaid means to prevent false operation of said clearing-out or supervisory signaling apparatus. 35

10. A telephone exchange system including telephone lines extending from sub-stations to different exchanges, a voice-current-conveying trunk circuit for uniting said lines in conversation, said trunk circuit being formed in sections that are un-united metallically but are united telephonically, clearing-out or supervisory signaling apparatus at one exchange adapted for association with one of said sections of the trunk circuit in the process of establishing a connection through said latter exchange, means associated with the other section of said trunk circuit for governing the aforesaid supervisory or clearing-out signaling apparatus, an operator's telephone equipment adapted for connection with the section of the trunk circuit which is metallically connected with said supervisory or disconnect signaling apparatus, and switching mechanism for including the operator's telephone equipment in circuit relation with the answering end of the trunk circuit, and serving to prevent effective operation of the aforesaid means 40 to prevent false operation of said clearing-out or supervisory signaling apparatus. 45

8. A telephone exchange system including telephone lines extending from sub-stations to different exchanges, a voice-current-conveying trunk circuit for uniting said lines in conversation, said trunk circuit being formed in sections that are un-united, metallically but are united telephonically, clearing-out or supervisory signaling apparatus 50 at one exchange adapted for association with one of said sections of the trunk circuit in the process of establishing a connection through said latter exchange, means associated with the other section of said trunk 55 circuit for governing the aforesaid supervisory or clearing-out signaling apparatus, an operator's telephone equipment adapted for connection with the section of the trunk circuit which is metallically connected with 115 said supervisory or disconnect signaling apparatus, and switching mechanism for limiting the operator's telephone equipment to association with the connecting end of the trunk circuit and serving to prevent operation of the aforesaid means to prevent false 120 operation of said clearing-out or supervisory signaling apparatus.

11. A telephone exchange system includ- 60 ing telephone lines extending from sub-stations to different exchanges, a voice-current-conveying trunk circuit for uniting said lines in conversation, said trunk circuit being formed in sections that are un-united me- 65 125 130

tallically but are united telephonically, clearing-out or supervisory signaling apparatus at one exchange adapted for association with one of said sections of the trunk circuit in the process of establishing a connection through said latter exchange, a bridge adapted for association with the latter trunk circuit section and governed for the purpose of preventing false operation of said clearing-out or supervisory apparatus and permitting the proper operation of said clearing-out or supervisory signaling apparatus by other apparatus, a switching device for opening and closing said bridge conductor, a signal device associated with the trunk circuit and operable from the exchange to which the trunk circuit extends, and relay mechanism at the trunk circuit station for dissociating said signaling device, said relay mechanism also governing the said bridge.

12. A telephone exchange system including telephone lines extending from sub-stations to different exchanges, a voice-current conveying trunk circuit for uniting said lines in conversation, said trunk circuit being formed in sections that are un-united metallically but are united telephonically, clearing-out or supervisory signaling apparatus at one exchange adapted for association with one of said sections of the trunk circuit in the process of establishing a connection through said latter exchange, a bridge adapted for association with the latter trunk circuit section and governed for the purpose of preventing false operation of said clearing-out or supervisory apparatus and permitting the proper operation of said clearing-out or supervisory signaling apparatus by other apparatus, a switching device for opening and closing said bridge conductor, an operator's telephone equipment adapted for connection with the section of the trunk circuit which is metallically connected with said supervisory or disconnect signaling apparatus, and electro-magnetic mechanism governed by a trunk circuit apparatus, for dissociating said operator's telephone from the trunk circuit and governing said bridge.

13. A telephone exchange system including telephone lines extending from sub-stations to different exchanges, a voice-current conveying trunk circuit for uniting said lines in conversation, said trunk circuit being formed in sections that are un-united metallically but are united telephonically, clearing-out or supervisory signaling apparatus at one exchange adapted for association with one of said sections of the trunk circuit in the process of establishing a connection through said latter exchange, a bridge adapted for association with the latter trunk circuit section and governed for the purpose of preventing false operation of said clearing-out or supervisory apparatus

and permitting the proper operation of said clearing-out or supervisory signaling apparatus by other apparatus, a switching device for opening and closing said bridge conductor, an operator's telephone equipment adapted for connection with the section of the trunk circuit which is metallically connected with said supervisory or disconnect signaling apparatus, and switching mechanism for including the operator's telephone equipment in circuit with the trunk circuit and serving to govern said bridge.

14. In a telephone exchange system including telephone lines extending from sub-stations to different exchanges; a voice-current conveying trunk circuit for uniting said lines in conversation, said trunk circuit being formed in sections that are un-united metallically but are united telephonically, clearing-out or supervisory signaling apparatus at one exchange adapted for association with one of said sections of the trunk circuit in the process of establishing a connection through said latter exchange, a bridge adapted for association with the latter trunk circuit section and governed for the purpose of preventing false operation of said clearing-out or supervisory apparatus and permitting the proper operation of said clearing-out or supervisory signaling apparatus by other apparatus, a switching device for opening and closing said bridge conductor, an operator's telephone equipment adapted for connection with the section of the trunk circuit which is metallically connected with said supervisory or disconnect signaling apparatus, and switching mechanism for including the operator's telephone equipment in circuit relation with the answering end of the trunk circuit and serving to govern said bridge.

15. A telephone exchange system including telephone lines extending from sub-stations to different exchanges, a voice-current conveying trunk circuit for uniting said lines in conversation, said trunk circuit being formed in sections that are un-united metallically but are united telephonically, clearing-out or supervisory signaling apparatus at one exchange adapted for association with one of said sections of the trunk circuit in the process of establishing a connection through said latter exchange, a bridge adapted for association with the latter trunk circuit section and governed for the purpose of preventing false operation of said clearing-out or supervisory apparatus and permitting the proper operation of said clearing-out or supervisory signaling apparatus by other apparatus, a switching device for opening and closing said bridge conductor, an operator's telephone equipment adapted for connection with the section of the trunk circuit which is metallically connected with said supervisory or disconnect

signaling apparatus, and switching mechanism for including the operator's telephone equipment in circuit relation with the connecting end of the trunk circuit and serving 5 to govern said bridge.

16. A telephone exchange system including telephone lines extending from sub-stations to different exchanges, a voice-current-conveying trunk circuit for uniting said lines in 10 conversation, said trunk circuit being formed in sections that are un-united metallically but are united telephonically, clearing-out or supervisory signaling apparatus at one exchange adapted for association with one 15 of said sections of the trunk circuit in the process of establishing a connection through said latter exchange, a bridge adapted for association with the latter trunk circuit section and governed for the purpose of preventing 20 false operation of said clearing-out or supervisory apparatus and permitting the proper operation of said clearing-out or supervisory signaling apparatus by other apparatus, a switching device for opening 25 and closing said bridge conductor, an operator's telephone equipment adapted for connection with the section of the trunk circuit which is metallically connected with said supervisory or disconnect signaling apparatus, and switching mechanism for limiting 30 the operator's telephone equipment to association with the answering end of the trunk circuit and serving to govern said bridge.

35 17. A telephone exchange system including telephone lines extending from sub-stations to different exchanges, a voice-current-conveying trunk circuit for uniting said lines in conversation, said trunk circuit being formed in sections that are un-united metallically but are united telephonically, clearing-out or supervisory signaling apparatus at one exchange adapted for association with one of said sections of the trunk 40 circuit in the process of establishing a connection through said latter exchange, a bridge adapted for association with the latter trunk circuit section and governed for the purpose of preventing false operation 45 of said clearing-out or supervisory apparatus and permitting the proper operation of said clearing-out or supervisory signaling apparatus by other apparatus, a switching device for opening and closing said 50 bridge conductor, an operator's telephone equipment adapted for connection with the section of the trunk circuit which is metallically connected with said supervisory or disconnect signaling apparatus, and switching 55 mechanism for limiting the operator's telephone equipment to association with the connecting end of the trunk circuit and serving to govern said bridge.

60 18. A telephone exchange system includ-

ing telephone lines extending from substations to different exchanges, a voice-current-conveying trunk circuit for uniting said lines in conversation, said trunk circuit being formed in sections that are un-united metallically but are united telephonically, 65 clearing-out or supervisory signaling apparatus at one exchange adapted for association with one of said sections of the trunk circuit in the process of establishing a connection through said latter exchange, means 70 associated with the other section of said trunk circuit for governing the aforesaid supervisory or clearing-out signaling apparatus, and operator-controlled switching mechanism associated with the section of the 75 trunk circuit that is not metallically connected with the supervisory or disconnect signaling apparatus, for preventing false operation of said clearing-out or supervisory signaling apparatus.

80 19. A telephone exchange system including telephone lines extending from sub-stations to one exchange, telephone lines extending from sub-stations to a second exchange, a trunk circuit extending between 85 said exchanges and having operator-controlled means at the first exchange for connecting it with telephone lines extending to the first exchange, a signal device in the trunk circuit, means at the second exchange 90 for impressing signaling current upon telephone lines extending thereto and upon said trunk circuit-signaling device, means at the first exchange for impressing signaling current upon telephone lines extending thereto, 95 and means for preventing operating signaling current from passing to a telephone line connected with the trunk circuit at the first exchange when said means at the second exchange 100 is operated, without preventing the 105 signaling current passing to said trunk circuit-signaling device.

110 20. A telephone exchange system including telephone lines extending from sub-stations to one exchange, telephone lines extending from sub-stations to a second exchange, a trunk circuit extending between 115 said exchanges and having operator-controlled means at the first exchange for connecting it with telephone lines extending to the first exchange, a signal device in the trunk circuit, means at the second exchange for impressing signaling current upon telephone lines extending thereto, 120 and upon said trunk circuit-signaling device, means at the first exchange for impressing signaling current upon telephone lines extending thereto, and electromagnetic mechanism governed by the trunk circuit-signaling device for preventing operating signaling current from 125 passing to a telephone line connected with the trunk circuit at the first exchange when said means at the second exchange is oper-

ated, without preventing the signaling current passing to said trunk circuit-signaling device.

21. A telephone exchange system including telephone lines extending from sub-stations to one exchange, telephone lines extending from sub-stations to a second exchange, a trunk circuit extending between said exchange and having means governed by the operator's listening switch at the first exchange for connecting it with telephone lines extending to the first exchange, link circuits at the second exchange for uniting lines extending thereto, clearing-out or

supervisory signaling apparatus associated 15 with said link circuits, and means governed by the operator's listening switch at the first exchange for preventing the operation of said supervisory or clearing-out signaling apparatus at the second exchange. 20

In witness whereof, I hereunto subscribe my name this eleventh day of March, A. D., 1909.

ELMER R. CORWIN.
